UNITED STATES PATENT OFFICE.

LOUIS S. ZEBROCK, JR., OF HASTINGS, NEW YORK.

PEN AND PENCIL ATTACHMENT

1,343,245.

Specification of Letters Patent. Patented June 15, 1920.

Application filed November 7, 1919. Serial No. 336,253.

To all whom it may concern:

Be it known that I, LOUIS S. ZEBROCK, Jr., a citizen of the United States, residing at Hastings, in the county of Westchester and State of New York, have invented certain new and useful Improvements in Pen and Pencil Attachments, of which the following is a specification.

My invention relates to new and useful improvements in a pen or pencil attachment and has for its principal object the provision of a device which may be attached to a pen or pencil and receive a finger or thumb of the hand of the user whereby the pen or pencil may be guided for writing properly.

Another object of the invention resides in the construction of a device which is adjustable so as to be adapted for pens or pencils of different diameters.

A further object of the invention resides in the provision of means for folding the attachment so that the pen or pencil, with the attachment in position, may be inserted in the pocket of the user.

With these and other objects in view my invention consists in the novel details of construction and arrangement of parts which will be more clearly understood from the following specification and drawings in which:—

Figure 1 is perspective showing a pen with my attachment in position.

Fig. 2 is an end elevation, and

Fig. 3 is a top plan.

In the drawings the numeral 1 indicates a pen holder with my attachment in position ready for use. The attachment comprises a flexible metal strip 2 which is adapted to be bent so as to form the cylindrical portion 3. As shown, more particularly in Fig. 2 of the drawings, the end 4 of the cylindrical portion will normally engage the top face of the plate 2. The pen 1, or pencil, will be placed through the cylindrical portion 3, as more particularly illustrated in Fig. 3 of the drawings, and the diameter of the cylindrical portion 3 may be reduced by pressure so as to slide the end 4 over the face of the plate 2. By this arrangement the cylindrical portion may be adjusted to adapt itself to pens or pencils of various diameters.

A plate 5 is hingedly connected to the plate 2 at 6 and the end of the plate 5 is

curved upwardly as indicated at 7 to form the end 8 which normally overlies the plate 5 as more particularly illustrated in Fig. 2 of the drawings. As is illustrated more particularly in Fig. 3 of the drawings, the curved portion 7 extends at an angle so as to properly receive the finger of the user in a manner to be later described. As is illustrated in Fig. 2 of the drawings the plate 5 is adapted to be swung upon the hinge 6 so that the curved portion 7 will overlie the top of the cylindrical portion 3 and the end 8 will engage the cylindrical portion so as to hold the parts in their adjusted or folded position. 70

From the above detailed description it is thought that the manner of using my device will be clearly understood as well as the advantages thereof. As previously stated the pen or pencil is adapted to pass 75 through the cylindrical portion 3 and said cylindrical portion may be adjusted to adapt itself to pens or pencils of various diameters. When the attachment is on the pen or pencil the finger is received in the 80 curved portion 7 of the plate 5 and the overlying end 8 will securely hold the attachment upon the finger. By this arrangement the pen or pencil is supported upon the finger and the pen or pencil may be 85 guided for writing properly. When using my attachment the finger will be held straight so as to prevent writers' cramp and will allow a free hand movement in writing. My attachment also makes it possible for a 90 person who has lost a finger or a number of fingers to write properly. If all four of the fingers have been lost the attachment may be applied to the thumb. The plate 5 is of flexible material, so as to be properly 95 curved, and may be flexed or adjusted to adapt itself to the different sized fingers of the user. When not in use the plate 5 may be swung upon the hinge 6 so that the curved portion 7 overlies the cylindrical 100 portion 3 and the end 8 will engage the cylindrical portion to hold the parts in their folded position. When folded the pen or pencil may be easily inserted into the pocket of the user. 105

The foregoing description and the drawings have reference to what may be considered the preferred or approved form of my invention. It is to be understood that I may make such changes in construction 110

and arrangement and combination of parts, materials, dimensions, etc., as may prove expedient and fall within the scope of the appended claims.

5 Having thus fully described my invention, what I claim as new and desire to secure by Letters Patent, is:—

1. A pen or pencil attachment comprising a plate having one edge curved to form 10 a cylindrical portion, the end of the cylindrical portion engaging the upper surface of the plate, and a second plate hingedly connected to the first mentioned plate, the edge of said second mentioned plate being 15 curved upwardly and inwardly.

2. A pen and pencil attachment comprising a pair of plates, one of said plates curved adjacent one edge so as to form a cylindrical portion, the other edge being provided with a hinge section, the second 20 plate hingedly connected to the hinge section and having its other edge curved upwardly and inwardly.

In testimony whereof I affix my signature in presence of two witnesses.

LOUIS S. ZEBROCK, JR.
